UNITED STATES PATENT OFFICE.

HENRY K. FOWHL, OF ALLEGHENY, PENNSYLVANIA.

FOLDING TABLE.

No. 830,314.

Specification of Letters Patent.

Patented Sept. 4, 1906.

Application filed January 13, 1906. Serial No. 295,876.

To all whom it may concern:

Be it known that I, HENRY K. FOWHL, a citizen of the United States of America, residing at Allegheny, in the county of Allegheny and State of Pennsylvania, have invented certain new and useful Improvements in Folding Tables, of which the following is a specification, reference being had therein to the accompanying drawings.

10 This invention relates to certain new and useful improvements in tables, and the primary object of the invention is to provide a novel form of folding or collapsible table which can be easily and quickly folded into 15 a compact form, whereby it will occupy a comparatively small space.

Another object of this invention is to provide a folding table that will be substantial in either form, but when folded will provide 20 a small oblong table capable of supporting various objects.

A further object of this invention is to provide a table which will be extremely simple in construction, strong and durable, comparatively inexpensive to manufacture, and one which when folded can be easily and quickly manipulated to provide a table.

With the above and other objects in view, which will more readily appear as the nature 30 of the invention is better understood, the same consists in the novel construction, combination, and arrangement of parts to be hereinafter more fully described and claimed, and referring to the drawings accompanying 35 this application like numerals of reference designate corresponding parts throughout the several views, in which—

Figure 1 is a front elevation of my improved table. Fig. 2 is a side elevation of 40 the same. Fig. 3 is a similar view of the table in a folded or "knocked-down" position. Fig. 4 is a detail sectional view of a portion of the table-top.

To put my invention into practice, I construct my improved table of a three-part 45 table-top 1 and two sets of legs 2 2. The table-top embodies a central section 3, to which are hinged end sections or flaps 4 4, the transverse edges of the end sections or flaps 4 4 being connected to the transverse edges 50 of the central section 3 by hinges 5 5. The transverse edges of the central section 3 of the table-top are provided with grooves 6 6 and tongues 7 7, the tongues 7 7 being adapted 55 to fit within grooves 8 8, formed in the transverse edges of the end sections or flaps

4 4, said sections being provided with tongues 9 9, adapted to fit in the grooves 6 6 of the central section 3, whereby when the sections 4 4 horizontally align with the section 3, as in 60 a "set-up" position, a smooth and interlocking joint will be formed between the sections 3 and 4 4.

To retain the sections in horizontal alignment with one another, I pivotally mount, 65 centrally of the section 3, a cleat 10, which is provided with a handle or knob 11, whereby it can be easily rotated to embrace the underneath faces of the sections 4 4, strengthening the hinged edges of said sections and 70 preventing the table from being folded or collapsed. The central section 3 at its one end is provided with a depending pin 12 to limit the movement of the cleat 10 in one direction, while one of the sections 4 is provided with a depending pin 14, adapted to 75 limit the movement of the cleat 10 in the other direction and position it transversely of the adjoining edges of the sections 3 and 4 4.

The legs 2 of each set consist of parts or members 15 15 and 16 16', the parts or members of each leg being connected together by hinges 17 17. The parts 15 15 are hinged, as at 18 18, to the end sections or 85 flaps 4 4 of the table, while the parts 16 16' of each set of legs are pivotally connected together, as at 19, upon the contracted ends 19^a of a rod 19^b, arranged between the sets of legs 2 2. The lower ends of the parts 16 16' 90 of each set of legs are bent downwardly, as at 20 20, to form a firm foundation for the table. The upper ends of the legs 16 16 of each set of legs are connected together by a transverse bar 21, while the upper ends of the 95 legs 16 16' of each set are braced from the transverse rod 19^b by angularly-disposed bars 22 22.

In Figs. 1 and 2 of the drawings I have illustrated the table in a set-up form, and 100 by referring particularly to Fig. 2 of the drawings it will be observed that the upper ends of the parts or members 15 15 of each set of legs are mitered to engage the underneath faces of the sections 4 4 and form a 105 horizontal support for said sections. When the sets of legs have been positioned as shown in Figs. 1 and 2 and the cleat 10 rotated to engage the sections 4 4, it will be impossible to "break" the joints of the parts 110 or members of the legs, this only being accomplished when the cleat is swung into

alinement with the central section 3 of the table-top 1. By bracing the sets of legs by the transverse rod 19^b and the bar 21, together with the bars 22 22, a substantial and 5 non-collapsible table is provided; but when it is desired to fold the same it is only necessary to swing the cleat in alinement with the central section 3, at which time the sets of legs, together with the sections 4 4, can be 10 swung to the position shown in Fig. 3. In this instance the lower ends of the members 16 16 and 16' 16' form supports for the table in a folded form, and when in this form it will be observed that the upper hinged ends 15 of the members or bars 15 15 and 16 16' of each set of legs provide a foundation for the central section 3 of the table-top, while the sections 4 4 are permitted to swing downwardly parallel with the legs of the table, 20 thereby providing a narrow oblong table, which will occupy a comparatively small space relative to the table in a set-up position.

What I claim, and desire to secure by Letters Patent, is—

1. A table of the type described embodying a table-top consisting of a central section, end sections hinged to said section, sets of

legs hinged to said end sections, each leg of each set of legs consisting of two hinged sections, a transverse rod pivotally connecting the lower of said hinged sections of each set of legs together, a transverse bar connecting each set of legs, a cleat pivotally mounted upon the bottom of the central section of the 30 top and adapted to engage the end sections of the top, substantially as described.

2. A table of the type described, comprising a central table-top section, end sections hinged to said central section, legs hinged in 40 pairs to said end sections, the legs of each pair being hinged each to the opposite end section, each leg formed of two sections hinged together, a rod pivotally connecting the lower sections of each pair of legs together, and means to hold said end sections of the table-top in horizontal alinement with the central section of said table-top, substantially as described.

In testimony whereof I affix my signature 50 in the presence of two witnesses.

HENRY K. FOWHL.
